UNITED STATES PATENT OFFICE.

HOWARD T. BLAESE, OF PHILADELPHIA, PENNSYLVANIA.

SUPPLEMENTARY FRONT FOR STOVE OVENS.

Application filed January 26, 1922. Serial No. 531,831.

To all whom it may concern:

Be it known that I, HOWARD T. BLAESE, a citizen of the United States, residing at Philadelphia, in the county of Philadelphia and State of Pennsylvania, have invented new and useful Improvements in a Supplementary Front for Stove Ovens, of which the following is a specification.

My invention relates to new and useful improvements in a supplementary front for stove ovens, and has for its object to provide a device of this character which is particularly adapted for use with the ovens of gas ranges whereby the articles being cooked may be watched during the cooking process.

Another object of the invention is to provide a supplementary front having transparent sights.

A further object of the invention is to provide a device of this character which may be readily and quickly positioned or removed and which will be securely held against accidental displacement during the time it is in use.

A still further object of the invention is to construct a supplementary front of the class described consisting of a front plate having openings therethrough adapted to be covered with transparent sheets of material, preferably glass, held in place by clips secured to the front plate in any suitable manner so as to form a channel to receive the edges of the glasses with strips of asbestos in the channels so as to pack the edges of the glasses to keep the metal and glass out of contact, pack the spaces between the elements to prevent the escape of heat and to permit expansion and contraction of the glass without the likelihood of the same becoming broken and to provide resilient holding members at the upper end of the device for engagement of the walls of a stove oven to maintain the device in position during use.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings

forming a part of this application, in 55 which:—

Fig. 1, is a perspective view of a gas range illustrating the application of my invention to the oven portion thereof.

Fig. 2, is an enlarged face view of a supplementary front embodying my invention.

Fig. 3, is a top edge view thereof.

Fig. 4, is a section at the line 4—4 of Fig. 2.

In carrying out my invention as here embodied, 2 represents a stove here illustrated as a gas range provided with an oven 3 having a doorway 4 in the front thereof which is normally closed by a door 5 hinged thereto in any suitable or well known manner and 6 denotes a supplementary front adapted to be removably mounted in the doorway 4 of the oven during which time the door 5 is preferably left open although the manner in which gas ranges are constructed at the present 75 time said door could be closed with the supplementary front in place.

The supplementary front comprises a front plate 7 of such size and shape as to cover the doorway or snugly fit within the same when disposed across doorway and this front plate has one or more openings or windows 8 formed therein, said openings being preferably two in number as here shown, in the ordinary domestic cooking 85 range.

On the rear face of this front plate are secured a number of upright clips 9 Z-shaped in cross section, one of which is arranged adjacent the side edge of the opening or openings 8 and held in place by suitable fastening means 10 here represented as rivets for convenience of illustration. Similar clips 11 are secured by fastening means 10 to the rear face of the front plate adjacent the top and bottom edges of the opening or openings 8 and where more than one opening is formed in the front plate these last named clips are preferably of sufficient length to extend across all of the openings and the 100 upright clips. The outer edges of the clips which are situated adjacent the outer edges of the front plate terminate short of the outer edges of said front plate so as to produce an overhanging edge 12 beyond the 105 clips and said overhanging edge preferably engages the outer face of the stove oven while the clips project into said oven.

The clips when fastened to the front plate form channels with said front plate which entirely surround the opening or openings 8 and hold the transparent sheets 13 preferably 5 glass in proper position across the opening or openings 8, the edges of said transparent strips being surrounded by asbestos or other suitable equivalent packing 14 which is disposed between the edges of the transparent strips and the faces adjacent thereof and the surrounding metal parts. This packing 10 will prevent the escape of heat from the oven and is also sufficiently compressible to permit expansion and contraction of the 15 transparent strips without said strips pointing upon the surrounding metal and being cracked or broken.

Adjacent the upper end of the supplementary front at each of its side edges is 20 secured a resilient holding member 15 having a foot 16 for attachment to the rear face of the device and an outwardly bowed body portion 17 for frictionally engaging the inner walls of the oven to prevent accidental 25 displacement of the supplementary front while in use.

In order that the device may be readily handled, I provide a loop 18 which is attached to the outer face of the front plate 30 by means of one of the aforementioned fastening devices and in this loop is mounted a ring 19 which may be swung into different positions as will be obvious.

In practice during the process of baking 35 bread, pies, cake and the like it is desirous that the articles be visible in order to watch the progress of the baking process without having to open the oven as such opening of the oven causes it and the articles therein 40 to become chilled and in some cases causes the objects to "fall" making the resultant product coarse and heavy. It has been found to be a great disadvantage to provide an oven with a glass door where such 45 an oven is to be used for all kinds of cooking because during a roasting process the temperature must be considerably higher than for baking and the grease thrown off clouds the glass fronts and in some cases 50 is actually burned into the glass so that it cannot be properly cleansed to give a clear vision of the interior of the oven. These disadvantages are entirely overcome by the use of my device since it is designed for only 55 temporary use, the same being placed in position only when it is desirous or necessary to note the progress of the cooking process without the necessity of opening the door.

Of course I do not wish to be limited to 60 the exact details of construction as herein

shown as these may be varied within the limits of the appended claims without departing from the spirit of my invention.

Having thus fully described by invention, what I claim as new and useful is: —

1. As an article of manufacture, a supplementary stove oven front comprising a frame including transparent material and resilient holding means adapted to engage the inner walls of an oven for removably 70 mounting said front in the oven doorway.

2. As an article of manufacture, a supplementary front consisting of a plate having openings therethrough covered with transparent material and having resilient 75 holding members for frictionally engaging the walls of an oven to detachably mount said front in the oven doorway.

3. In a device of the character stated, a supplementary front for stoves comprising so in combination a front plate having openings therein, clips secured to the rear face of the front plate adjacent the edges of the openings and forming channels surrounding said openings, said clips being set back 85 from the edges of the front plate to produce overhanging edges, glass strips mounted in said channels and disposed across the openings, asbestos packing surrounding the edges of said glass strips within the channels to 90 prevent the escape of heat and permit expansion and contraction of the glass strips, a resilient holding member secured to the rear face of the front plate at each side thereof adjacent its upper end and projecting rearwardly therefrom for frictional engagement with the inner walls of an oven to which the device is temporarily connected, a loop secured to the front face of the front plate at its upper end and a ring attached 100 to said loop.

4. In a device of the character stated, a front plate having openings formed therethrough, transparent strips disposed across said openings, means attached to the plate 105 for holding said strips in place and resilient holding means secured at the sides of said front plate adjacent its upper end for temporarily holding the front plate in the doorway of a stove oven.

5. As an article of manufacture, a supplementary stove oven front comprising a plate and resilient holding members for frictional engagement with the walls of a stove oven to temporarily hold the oven front in the 115 doorway of the stove oven.

In testimony whereof, I have hereunto affixed my signature.

HOWARD T. BLAESE.
